Des. 210,909
Patented Apr. 30, 1968

210,909

POOL COVER ANCHOR

Henry A. Patnaude, 831 Los Molinos Way,
Sacramento, Calif. 95825

Filed Aug. 17, 1967, Ser. No. 8,310

Term of patent 14 years

(Cl. D54—11)

FIG. 1.

FIG. 2.

FIG. 3.

FIG. 4.

FIG. 5.

I claim:

The ornamental design for a pool cover anchor, substantially as shown and described.
